UNITED STATES PATENT OFFICE.

FRANCIS J. PLYM, OF NILES, MICHIGAN, ASSIGNOR TO KAWNEER MANUFACTURING COMPANY, OF NILES, MICHIGAN, A CORPORATION OF MICHIGAN.

AEROPLANE-WING CONSTRUCTION.

1,337,951.

Specification of Letters Patent. Patented Apr. 20, 1920.

Application filed October 11, 1918. Serial No. 257,781.

To all whom it may concern:

Be it known that I, FRANCIS J. PLYM, a citizen of the United States, residing at Niles, in the county of Berrien and State 5 of Michigan, have invented certain new and useful Improvements in Aeroplane-Wing Construction, of which the following is a specification.

This invention relates to aeroplanes and 10 more particularly to the wing features thereof. The desideratum in aeroplane construction, especially at the present time, is to effect conservation of wood by substituting metal therefor as far as possible without 15 impairing the efficiency of the machine, as the safety of operation demanded depends on speed and responsiveness to control as much as to strength and stability of construction.

20 The chief object of the invention is to produce a wing construction as light and as near fire-proof as possible consistent with strength and resiliency. A further object is to produce a wing in which the bulging 25 of the fabric covering shall be substantially minimized, and in which repairs to the covering may be made with the minimum cost for material and labor.

With these objects in view the invention 30 consists in certain novel and useful features of construction and combinations of parts as hereinafter described and claimed; and in order that it may be fully understood reference is to be had to the accompanying 35 drawings, in which:

Figure 1, is a fragmental plan view of an aeroplane of any approved type.

Fig. 2, is an end view of a wing of the aeroplane.

40 Fig. 3, is an enlarged section taken on the line III—III of Fig. 1.

Fig. 4, is a broken section taken on the line IV—IV of Fig. 1.

45 Fig. 5, is a fragmentary perspective view of the wing, with certain parts broken away.

Fig. 6, is an enlarged section on the dotted line VI of Fig. 5.

50 Fig. 7, is an enlarged fragmentary plan view of the rear part of the wing.

Referring to the drawing in detail, 1 indicates the body or fuselage and 2 the propeller of an aeroplane of any approved type, and 3 designates the wing of the machine, which, of course, may be a multiple

wing machine, such as a biplane or a triplane.

The wing comprises two or more parallel metal beams 4 of skeleton construction. They extend from one end of the plane or 60 wing to the other, and due to the cross sectional form of the latter, the depth of the beams is different, as the wings are thicker near their front than near their rear ends. Each beam preferably consists of channel 65 bars 5 arranged with their channels facing each other and spaced apart and braced by a zig-zag metal bracing strip 6 to give the greatest strength consistent with lightness, the adjacent ends of converging portions of the strip being connected by short portions 7, conforming to and fitting in the channels of bars 5, to provide ample fastening space. At suitable intervals cross ribs are arranged, these ribs in side view 70 determining the cross sectional form of the wing, and each preferably consists of a channeled metal bar 8 bent or doubled to form a rounded front end or nose, a slightly concaved underside and a convex upper side, 75 with said sides tapering rearwardly and terminating within a channeled trailing edge strip 9 arranged parallel with the beams 4, the arms or sides of the doubled strip 8 being rigidly secured together and properly spaced by a zig-zag bracing strip 10, of the same type as bracing strip 6. The ribs are arranged to intersect the beams, with the latter extending through the ribs, 80 and suitably interlocked therewith in any 90 desired manner.

The bars 8 are incased at their outer sides by channeled covering strips 11, of resilient metal, and the flanges of said covering strips are rebent at their margins to form channels 12.

To stiffen the framework and form a partial support for the covering hereinafter described, and act to guard against distortion or bulging of the covering, channeled 100 nose plates 13 extend from rib to rib at the front ends thereof, and conform to the nose-shaped contour of such ends, and said plates are provided with inturned flanges 14 at their ends to engage the channels or grooves 105 12. The cover, preferably of fabric, is made in sections 15 of slightly greater width than the spaces between adjacent ribs so that the side margins of said sections shall overlap the channels or grooves 12, and to secure 110

said sections, which of course extend around the nose plates 13 as shown, and underlie and overlie the beams and trailing edge strip 9, wire rods 16 are fitted over the sections 15 and into the channels or grooves 12 to clamp the marginal portions of the sections within the grooves 12, the ends of each wire rod being twisted or otherwise secured together at 17, so that they shall 10 be incapable of working out of the grooves or channels and releasing the fabric covering sections.

From the above description it will be apparent that I have produced a wing construction for aeroplanes which possesses all of the merits of a wood construction and in addition thereto greater strength, more resistance to destruction by fire or shock, and the great advantage of quick, easy and inexpensive repair in the event of injury to only a part or parts of the cover, as it is obvious that any section of the latter may be removed and replaced without disturbing any other section.

It will be understood of course that I reserve the right to make such changes as may properly fall within the principle of construction involved and the spirit and scope of the appended claims.

I claim:

1. In an aeroplane, a wing comprising intersecting beams and ribs, a trailing edge strip connecting the rear ends of said ribs, strips fitting around the ribs and provided

at their side margins with channels, nose 35 plates bridging the spaces between said strips and secured in rigid relation thereto, cover sections between said strips and fitted at their side margins in said channels, and wires engaging said channels and cover sections and clamping the latter firmly within said channels.

2. In an aeroplane, a wing comprising intersecting beams and ribs, a trailing edge strip connecting the rear ends of said ribs, 45 nose plates bridging the spaces between said ribs and provided with flanges adjacent the ribs, strips fitting around the ribs and provided with side channels receiving the flanges of the nose plates, cover sections 50 between said strips and around said nose plates and fitting in the channels of the strips, and means securing the side edges of the cover sections within said channels.

3. In an aeroplane, a wing comprising 55 intersecting beams and ribs, a trailing edge strip connecting the rear ends of the ribs, strips fitting around the ribs and provided with side channels, nose plates connecting the front ends of said strips and provided 60 with flanges engaging said channels, cover sections fitting between said strips and around said nose plates and within said channels, and wires engaging said channels and clamping the side edges of the cover 65 sections firmly within said channels.

In testimony whereof I affix my signature.

FRANCIS J. PLYM.
